UNITED STATES PATENT OFFICE.

FRANK DOUGLAS, OF NORWICH, CONNECTICUT.

IMPROVEMENT IN GOVERNORS FOR STEAM-ENGINES.

Specification forming part of Letters Patent No. 39,799, dated September 8, 1863.

To all whom it may concern:

Be it known that I, FRANK DOUGLAS, of Norwich, in the county of New London and State of Connecticut, have invented a new and Improved Regulator for Steam-Engines; and I do hereby declare that the following is a full, clear, and exact description of the same, reference being had to the accompanying drawings, making a part of this specification, in which—

Figure 1 is a perspective view of a horizontal engine with regulator and link attached. Fig. 2 is a vertical section of the regulator cut through the center.

Similar letters of reference indicate corresponding parts of both figures.

The object of my invention is to produce a regulator that will move a link, or any other arrangement that takes a considerable amount of power up and down with ease, and maintain a steady motion of the engine; also, a link (that is moved by the regulator) that hangs on centers and slides up and down through a box connected to valve-rod, and is provided with set-screws and gib to take up lost motion.

A A A is the regulator frame and stand; B B, the regulator-balls; c c c, regulator-arms; D, the block to which the upper ends of arms are hung. E, the driving-pulley, turns spindle F, which has a bearing at the upper end through frame A A, and on lower end by fitting into the socket f in upper end of screw-arbor g, thus forming a guide for the upper end of arbor and lower end of spindle. Block D is attached to spindle F by set-screw H. The clutch-block i, to which the lower ends of arms c c are attached, turns freely on arbor g. The centrifugal force of regulator throws the block i up and clutches into clutch-collar K, that is firmly attached to screw-arbor g, thus causing the arbor g to turn with the block i until it screws itself up out of clutch, when the block i is allowed to play freely between the clutches. When the centripetal force of the balls throws the block i down into the clutches of collar M, which is firmly attached to the stem of the upper bevel-gear, N, that plays freely through box o and on arbor g. Gear N meshes into the intermediate gear, P,

which meshes into the lower gear, R, that is firmly attached to the arbor g, but plays freely through box o, thus turning the screw down through nut L until it runs itself out of clutch and leaves the block i playing freely between the clutch-collars as before. On the lower end of screw-arbor g is attached the spade handle joint S and connection T, jointing onto rod U, said rod having a strap, 8, around the main shaft of engine at one end, and connected by the pin b to the lower end of link V, thus holding the link still at lower end, while the motion is given to the valves by the eccentric rod W, which is also hung central on upper end of link by pin b. The valve rod x plays through the square sleeve y and connects on both sides of box 2 by pins 3 3. Link V slides freely up and down through the box 2. Gib 4 and set-screws 5 5 are to take up lost motion. Yoke 6 on regulator is provided with spaces j j, through which arms c c passes, to prevent the block i from running up or down farther than the given point indicated by spaces j j. Box o, that contains bevel-gears, slides up and down on guides 7 7.

The operation is as follows: When there is centrifugal force enough to raise clutch-block i and clutch into clutch-collar K, it turns the screw-arbor g until it runs up out of clutch, taking connection U, and link V as far as the balls B B indicate. When the balls drop and clutch-block i clutches into collar M, the bevel-gear, in box o reverses the motion of screw g and runs the link down. When the regulator has heavy work to perform, the clutches are made on such an angle as to make the inclination as great to slide off as to cling onto the clutches, thereby making the work of the balls B B but the lifting and lowering of the clutch-block i. When the link V is run up by the regulator-screw g, it makes the throw of the slide-valve less and cuts off the steam at the point of stroke thus indicated, thereby precluding the necessity of any other regulator or cut-off valves and making the slide-valve a perfectly-working variable cut-off.

What I claim, and desire to secure by Letters Patent, is—

1. The screw-arbor g, movable clutch-collars

K and M, and clutch-block *i*, when used in combination with the box *o*, and bevel-gears N, P, and R, the whole combined to operate as described, so that the clutch-collars K and M may be caused to run up or down out of clutch and allow clutch-block *i* to remain at any joint indicated by the regulator-balls.

2. The guide-socket *f*, when used to form a

guide for spindle F and screw arbor *g*, as described.

3. The manner of suspending the link V, as herein specified.

FRANK DOUGLAS.
